GOLF CLUB CARRIER

Harold W. Darr, Minneapolis, Minn., assignor to Ridgway Baker, Minneapolis, Minn.

Application May 16, 1949, Serial No. 2,691

Term of patent 14 years

(Cl. D14—3)

To all whom it may concern:

Be it known that I, Harold W. Darr, a citizen of the United States, residing at Minneapolis, in the county of Hennepin and State of Minnesota, have invented a new, original, and ornamental Design for a Golf Club Carrier, of which the following is a specification, reference being had to the accompanying drawing, forming part thereof.

Referring to the drawing:

Fig. 1 is a view in top and front perspective of a golf club carrier incorporating my new design;

Fig. 2 is a top plan view of the golf club carrier of Fig. 1; and

Fig. 3 is a bottom plan view of the golf club carrier of Fig. 1.

I claim:

The ornamental design for a golf club carrier, as shown.

HAROLD W. DARR.
